Inventor:

Wm. H. Miller

United States Patent Office.

WILLIAM H. MILLER, OF PHILADELPHIA, PENNSYLVANIA.

Letters Patent No. 64,688, dated May 14, 1867.

IMPROVEMENT IN FIBROUS PACKING FOR STEAM ENGINES.

The Schedule referred to in these Letters Patent and making part of the same.

TO ALL WHOM IT MAY CONCERN:

Be it known that I, WILLIAM HARTLEY MILLER, of the city of Philadelphia, and State of Pennsylvania, have invented a new and useful improvement in Stuffing-Box Packing; and I do hereby declare that the following is a full, clear, and exact description of the same, reference being had to the annexed drawings making a part of this specification, in which—

E represents a piece of my improved packing.

My invention consists of a packing of hemp, cotton, or other fibrous material, made into a single strand, in the form of harl or roving, and covered with a muslin or braided cover.

I form the harl or roving of any required diameter and length, in the usual manner, and then cover this roving with a muslin cover, or by means of a harding machine with a braided cover.

Having thus described my invention, I claim, and desire to secure by Letters Patent, as a new article of manufacture—

A packing, consisting of a hemp, cotton, or other fibrous filling, made into the form of a harl or roving, and covered with a fibrous cover, substantially as described.

WM. HARTLEY MILLER.
